UNITED STATES PATENT OFFICE.

SAMUEL A. VAN OSDEL, OF JOHNSON, NEBRASKA.

SURGICAL INSTRUMENT.

Application filed December 6, 1920. Serial No. 428,538.

To all whom it may concern:

Be it known that I, SAMUEL A. VAN OSDEL, a citizen of the United States, and a resident of Johnson, county of Nemaha, 5 State of Nebraska, have invented certain new and useful Improvements in Surgical Instruments, of which the following is a specification.

This invention relates to surgical instruments, and is shown and described herein as embodied in an instrument of special utility in removing tonsils or other parts of the throat comparatively difficult of access, it being understood that by slight changes 15 in the details of construction such as the size and shape of the parts, it may be adapted for other uses.

Unless tonsils are comparatively prominent, they cannot be completely removed by 20 a flat instrument, because of the engagement of the instrument with the faucial pillars of the throat, and if a flat instrument is used it is necessary to force the tonsil into proper position between the cooperating 25 edges of the instrument, with consequent inconvenience to the patient and to the operator. If the tonsils are embedded, it is frequently necessary to dissect them by hand, the operation being tedious and resulting in much pain and great danger of 30 severe hemorrhage.

One of the objects of this invention is to provide a simple and efficient instrument for completely removing such relatively 35 inaccessible parts, which can be readily positioned upon the part to be removed. Another object of the invention is to provide an instrument of this type by which a powerful crushing action can be effected and 40 sustained, to lessen the loss of blood, and the part be then severed by a distinct cutting action. A still further object is the provision of an instrument of this type which can be readily operated by either hand, which 45 is of simple construction, and can be readily disassembled and cleaned, and which can be adapted for various uses by replacing certain of the parts.

Still further objects of the invention and 50 the features of novelty will be apparent from the following specification when taken in connection with the accompanying drawings, in which:

Fig. 1 is a side elevation of an instrument 55 embodying my invention, a portion of the handle being broken away and certain of

the parts being shown as moved slightly from normal position, to more clearly disclose the structure;

Fig. 2 is a fragmentary plan view of the 60 forward end of the structure shown in Fig. 1;

Fig. 3 is an enlarged transverse vertical section taken on line 3—3 of Fig. 1, looking 65 in the direction of the arrow;

Fig. 4 is a vertical transverse section 70 taken on line 4—4 of Fig. 1, one of the parts being removed; and,

Fig. 5 is a fragmentary vertical longitudinal section taken on the line 5—5 of Fig. 2. 75

The instrument shown in the drawings comprises a frame having a straight forwardly projecting portion 11, provided with side walls 12, so as to be of channel shape in cross section, and having a handle 13 75 which may, if desired, be integral with the channeled portion 11, but is shown as detachably secured thereto to provide for the replacement of certain of the operating parts by parts of the shape and size desired. The 80 channeled portion 11 is formed with an extension 14, and the upper end of the handle is hollow, having a transverse wall 15 at its forward edge and spaced lateral walls 16, between which the extension 14 fits. A 85 thumbscrew 17 extends laterally through the walls 16 and the extension 14 to rigidly secure the parts together, the extension being held against the forward wall 15 of the handle and clamped between the side walls 90 16 thereof. The handle 13 is preferably formed with a guard or bow to form an opening in which the fingers may be inserted to facilitate handling of the instrument. 95

At its forward end, the channeled portion 11 carries a loop 18 which is rigid therewith and extends at an abrupt angle therefrom. A hemostat member is slidably carried by the frame, having a main portion 19, which 100 is received between the side walls 12 of the frame, and a loop 20 which projects from the main portion 19 and is shaped to conform to the shape of the loop 18 of the frame. A cutting member is also slidably carried by the frame, having a main portion 21, received between the side walls 12 of the frame, and a loop 22 which projects from the main portion 21 and fits in the loop 20 of the hemostat member. In order 105 that the hemostat member and cutting member may be properly guided on the frame,

the side walls 16 of the handle are formed with lugs 23, which extend inwardly therefrom to overlie the main portion 21 of the cutting member, and the side walls 12 of the 5 channelled portion 11 of the frame are formed with lugs 24, adjacent the loop 18, which also overlie the main portion 21 of the cutting member. The lugs 24 may, if desired, conform in shape to that of the 10 lugs 23, but the main portion 21 of the cutting blade is herein shown as cut away at its sides adjacent its forward end as shown at 25, and the lugs 24 are formed, as shown in Fig. 3, to overlie and engage both 15 the main portion 19 of the hemostat member and the main portion 21 of the cutting member. Provision is thus made for guiding the hemostat member when the cutting member has been removed, it being understood that 20 upon sliding the hemostat member out of the channelled portion 11, the cutting blade will fall and can then be withdrawn from the end of the frame, and the hemostat member, when replaced, will be held down by 25 the lugs 24.

An operating lever 26 is pivoted for swinging movement toward and from the handle 13, on a pin 27 which is mounted in the side walls 16 of the handle, the lever 26 having a bayonet slot 28 therein so it can be detachably engaged on the pin 27, and having a reduced extension 29, which extends through a slot 30, in the main portion 19 of the hemostat member and a similar 35 slot 31, in the main portion of the cutting blade. A spring 32 is detachably secured on the handle 13, a T-shaped projection 33 being provided on the handle and an elongated slot being formed in the spring 32, 40 so that the spring may be placed in position on the projection and rotated to the operative position shown. The free end of the spring engages a shoulder 34 on the lever 26 to resiliently hold the lever in pivotal relation on the pin 27 and swing away from 45 the handle 13. The extension 29 of the lever 26 is thus normally held in engagement with the extension 14 of the channelled portion 11 of the frame, and is sufficiently 50 extended to hold the hemostat member and the cutting member in assembled relation on the frame.

A lever 35 is formed with a bayonet slot so as to be detachably and pivotally 55 supported on a pin 36, which is mounted in the side walls 16 of the handle 13, and is formed with a narrowed extension 37, which is engaged in a slot 38 in the main portion 21 of the cutting member, so that this member 60 may be retracted by swinging the lever 35 toward the handle 13. A spring 39 is detachably carried by the lever 34, being mounted on a T-shaped projection 40 thereon in a manner similar to the mounting of 65 the spring 32 on the handle 13, and the free

end of the spring engages the pin 36 to yieldingly hold the lever 35 on the pin. As shown in Fig. 1, the main portion 21 of the cutting member may be formed with a transverse web 41, separating the slots 31 and 38 70 therein, for engagement by the forward edge of the extension 37, and a projection 42 may be formed on the pin 36 for engagement by the spring 39, so that the spring will yieldingly hold the extension 37 of the lever in 75 the extreme forward position and, by reason of the engagement of such extension with the web 41, will also yieldingly hold the cutting blade in its extreme forward position. 80

The loops 18 and 20 of the frame and hemostat member, respectively, being of the same size and shape, their meeting edges form opposed abutments, and their outer surfaces are tapered away from such abutments as shown in Figs. 1, 2, and 5. The inner surface of the loop 20 is similarly tapered to receive the loop 22 of the cutting member which conforms to such shape and is likewise tapered on its inner surface and 90 is also beveled to form a cutting edge 42, for shearing action with the inner edge of the abutment on the loop 18 of the frame. A portion of the inner surface of the loop 18 of the frame is of uniform contour to receive the loop 22 of the cutting member, but that portion thereof adjacent the rear edge of the loop may be formed with an inwardly inclined surface 43, as shown in 95 Fig. 5, for a purpose which will presently 100 appear.

In use the instrument is supported on either hand with the fingers inserted in the opening in the handle 13, the parts being in the position shown in Fig. 1, except that the loop 22 of the cutting member would be enclosed in the loop 20 of the hemostat member as shown in Figs. 2 and 5. The loops 18 and 20 may be engaged between the anterior and posterior faucial pillars of 110 the throat on opposite sides of the tonsil, and upon being gently pressed toward the tonsil, they will, by reason of the engagement of their slanting outer surfaces with the faucial pillars, pass around and close 115 back of the capsule of the tonsil, the tonsil being thus forced into position between the abutments on the loops. When the instrument has been properly positioned, the hemostat blade is retracted by gripping the 120 lever 26 toward the handle 13, the loop 20 being thus forced toward the loop 18 to exert a powerful crushing action of the tissues between the abutments of the loops. This action will thoroughly macerate the 125 compressed tissues and the pressure is sustained for a sufficient length of time to cause the walls of the blood vessels to stick together, permit the formation of blood clots and otherwise increase the hemostatic ac- 130

tion. After a suitable lapse of time the tonsil is severed by retracting the cutting blade by engagement of the thumb of the hand which holds the instrument with the lever 35, the sharpened edge 42 of the cutting blade cooperating with the inner edge of the abutment of the loop 18 to shear the clamped tissues and, by reason of the formation of the inclined inner surface 43 of 10 the loop 18 and of the oppositely inclined inner surface of the loop 22 of the cutting member, the severed part will be retained, thus obviating any danger of its being swallowed by the patient.

15 It will be apparent that the size and shape of the loops 18 and 20, as well as of the loop 22 of the cutting blade, will be determined by the conditions of the particular operation to be performed, and that parts 20 having loops of various sizes and shapes may be readily assembled in operative position upon the handle 13. It will also be apparent that, if the operations to be performed require, as for instance for removing 25 adenoids, substitute parts may be provided, having their relatively sliding parts, that is, the channeled portion 11 of the frame and the main portions 19 and 21 of the hemostat member and the cutting member, 30 uniformly curved in the required direction, and that, when positioned on the handle 13, such parts can be operated by the levers 26 and 35 in the manner described.

The instrument comprises few parts, and 35 these are of simple construction and can be readily disassembled and cleaned. It is capable of adaptation for a variety of operations, and enables the operator to completely remove embedded tonsils as effectively as if dissected out by hand, without the disadvantages entailed by that method.

While the structure and operation of one embodiment of the invention has been shown and described, it will be understood that 45 the changes suggested herein, as well as other changes in the details of construction, may be made without departing from the spirit of the invention which is defined in the appended claims.

50 The invention having been thus described, what is claimed is:

1. In a surgical instrument, the combination of a frame having a loop portion extending angularly therefrom to form an 55 abutment, a secondary cooperating member slidably carried by the frame, said member having a loop portion projecting angularly therefrom, for cooperation with said abutment, a blade carried by said frame and 60 having a portion fitting in one of said loops and having a cutting edge adapted to cooperate with the other of said loops, and means for operating said secondary cooperating member and said blade.

2. In a surgical instrument, the combination of a frame comprising a forwardly projecting portion and a portion offset therefrom to form a curved abutment, a secondary cooperating member having a portion 65 slidably engaged with the forwardly projecting portion of the frame and having thereon an offset portion movable toward and from the curved abutment of the frame, a blade carried by said frame and having a cutting edge conforming to the shape of said abutment, and means for operating said secondary cooperating member and said blade.

3. In a surgical instrument, the combination of a frame, a hemostat member slidably carried by said frame, said frame and said member having enlarged hollow end portions providing opposed abutments, a cutting member 80 slidable relative to said frame and having a portion fitting in one of said hollow end portions formed with a cutting edge for shearing action with the other hollow end portion, and means for sliding said hemostat member and said cutting member 85 relative to said frame.

4. In a surgical instrument for amputation, the combination of a frame, a member 90 slidably carried thereby, said frame and said member having hollow end portions formed with opposing abutments, means for moving said member relative to the frame to clamp the part to be severed between said abutments, a blade having a cutting edge for severing said part while so held, and means for operating said blade.

5. In a surgical instrument, the combination of a frame having a forwardly extending channeled portion and a loop portion 95 extending at an angle from said channeled portion, a secondary cooperating member having a portion slidably received in the channeled portion of the frame and having a loop portion conforming to the shape of the loop portion of the frame, a cutting member having a portion slidably received in the channeled portion of the frame and having a loop portion telescopically received in the loop portion of the secondary member 100 and formed with a cutting edge arranged for shearing action with the loop portion of the frame, and means for independently reciprocating said secondary member and said cutting member relative to said frame.

6. In a surgical instrument, the combination of a frame, a hemostat member slidably carried by said frame, said frame and said member having enlarged hollow end portions providing opposed abutments, a cutting member 110 slidable relative to said frame and having a portion formed with a cutting edge for shearing action with one of said abutments, the outer surfaces of said hollow end portions being tapered away from the abut-

ments thereon, and means for independently sliding said hemostat member and said cutting member relative to said frame.

7. In a surgical instrument, the combination of a frame having an abutment thereon and having a handle rigid therewith, a hemostat member carried by said frame for cooperation with said abutment, a cutting member carried by said frame, and a lever 10 pivoted for motion toward said handle for operating said hemostat member and a lever pivoted for motion toward said handle for operating said cutting member.

8. In a surgical instrument, the combination of a frame having a handle rigid therewith and having an abutment adjacent its forward end, a secondary cooperating member slidably supported on the frame and having an abutment opposed to the abutment of the frame, a cutting blade, means for operating said cutting blade, a lever movable toward said handle for operating said secondary member, said lever having a bayonet slot connection with said handle and 25 having an extension engaged in slots in said secondary member and said cutting member, and a spring cooperating with said lever

and said handle to hold them in pivotal relation, whereby said secondary member and said cutting member are held in assembled 30 relation on said frame.

9. In a surgical instrument for amputation, the combination of a frame and a hemostat member slidably carried thereby each comprising a body portion and a portion extending upwardly therefrom to form opposed abutments spaced from the body portion, a cutting member slidably carried by the frame and having a portion fitting in one of said upwardly extending portions 40 and formed with a cutting edge arranged for shearing action with the inner edge of the abutment of other of said upwardly extending portions, the inner surfaces of said other upwardly extending portion and of 45 that portion of the cutting member on which the cutting edge is formed being narrowed to retain the amputated part after it is severed, and means for independently sliding said hemostat member and said cutting member on said frame.

In testimony whereof I affix my signature.

SAMUEL A. VAN OSDEL.
